(57) **CLAIM**

An ornamental design for the actuator for a lifting device as shown and described.

DESCRIPTION

FIG. 1 is a bottom, rear and right perspective view of an actuator for a lifting device showing a first embodiment; FIG. 2 is a top, front and left perspective view thereof;

FIG. 3 is a bottom plan view thereof;

FIG. 4 is a top plan view thereof;

FIG. 5 is a left side view thereof;

FIG. 6 is a right side view thereof;

FIG. 7 is a rear view thereof;

FIG. 8 is a front side view thereof;

FIG. 9 is a bottom, rear and right perspective view of an actuator for a lifting device showing a second embodiment;

FIG. 10 is a top, front and left perspective view thereof;

FIG. 11 is a bottom plan view thereof;

FIG. 12 is a top plan view thereof;

FIG. 13 is a left side view thereof;

FIG. 14 is a right side view thereof;

FIG. 15 is a rear side view thereof; and,

FIG. 16 is a front side view thereof.

The broken-lines in the drawings depict portions of the actuator for a lifting device that form no part of the claimed design.
